UNITED STATES PATENT OFFICE.

CHARLES D. ORCUTT, OF NORTH TONAWANDA, NEW YORK, ASSIGNOR TO THE BUFFALO SLED COMPANY, OF NORTH TONAWANDA, NEW YORK, A CORPORATION OF NEW YORK.

SLED.

1,173,604.

Specification of Letters Patent. Patented Feb. 29, 1916.

Application filed May 20, 1915 Serial No. 29,332.

To all whom it may concern:

Be it known that I, CHARLES D. ORCUTT, a citizen of the United States, residing at North Tonawanda, in the county of Niagara and State of New York, have invented 5 new and useful Improvements in Sleds, of which the following is a specification.

This invention relates to a bob-sled incorporating simple and easily manipulated 10 means for yieldingly holding the steering runners in their central position by means of a single spring.

The object of the invention is to provide a conveniently operated, simple and strong 15 toy-sled having two sets of runners or bobs in which the movable runners may be normally held in their straight-forward position by one spring and yet which may be manually turned against the tension of the 20 spring to permit of steering; this object to be attained at comparatively low cost and with a minimum number of parts, requiring only the simplest machine work, so combined as to work smoothly and non- 25 erratically after the continued abuse to which such toys are subjected.

In the accompanying drawings Figure 1 is a side elevation of my improved bob-sled. Fig. 2 is a vertical longitudinal section taken along the middle of the same on line 2—2, Fig. 3. Fig. 3 is a bottom plan view of the sled demonstrating the steering method. Figs. 4 and 5 are fragmentary, vertical, transverse sections, on an enlarged scale, taken on lines 4—4 and 5—5, respectively, in Fig. 3. Fig. 6 is a fragmentary, horizontal section taken on line 6—6, Fig. 4, looking upwardly.

Similar characters of reference indicate 40 corresponding parts in the several views.

1 represents the body of my improved bob-sled which may be of any suitable construction but preferably comprises a light arrangement of the type shown, which consists of three transverse cleats 2 to which are secured two longitudinal side slats 3, a longitudinal central slat 4 projecting beyond the forward ends of said side slats, and two longitudinal hand bars 5 secured 45 to the outer ends of the cleats. This body may be supported in various ways by any number of bobs, one or more of which may be steerable depending on the weight to be sustained, but the usual construction consists of a fixed bob secured to the rear end 50

of the body and a forward bob capable of relatively horizontal turning movement. In the construction shown, each bob consists of two runners 9 arranged parallel to each other. From the rear part of each runner 60 a knee projects upwardly which comprises two slanting uprights 10 provided at their upper ends with an inwardly projecting arm 11. The arms of the rear bob are secured to the rear transverse cleat, while 65 the forward ends of the runners of said rear bob are secured to the hand bars 5, thereby fixing the rear bob securely to the body.

Each of the forward runners is provided with guiding means on the upper portion of 70 its knee which guiding means comprise a horizontal guiding plate 14 secured to said knee arm. King bolts 15 pass through the outer parts of the guiding plate, knee arm and the adjacent end of the forward transverse cleat, as shown in Figs. 1 and 5, thereby pivoting each runner separately to the body above the rear part of the sliding face of the respective front runner. Each guiding plate is provided at its inner end with 80 an arcuate slot 17 adapted to receive the guide screw 18 which is screwed into the lower side of the forward transverse cleat. Pivotally connected at its opposite ends to the forward ends of the front or steering 85 runners is a transverse yoke 19.

My steering mechanism is adaptable to turn a flexible steering bob which may be variously mounted on the body and its organization is such that it avoids the excessive cocking and the consequent jamming of the forward runners, when the same are turned to guide the bob around a sharp curve or over rough ground, and also provides convenient and positive means for 90 preventing the steering bob from twisting beyond the point where further turning will not increase the transverse turning movement tending to change the direction 95 of travel.

At the forward end of the sled and resting on the forward projecting end of the central longitudinal slat 4 is a transverse steering bar 20 to which is rigidly fastened a steering arm comprising upper and lower 100 arm sections 21 and 22, engaging the respective upper and lower surfaces of the transverse yoke 19. These arm sections turn integrally with the steering bar, being secured to the latter by means of two 110

rivets 23 and are provided at their forward ends with longitudinal slots 24 adapted to receive a pin 25 passing perpendicularly through the center of the transverse yoke, so that when the steering bar is turned, the steering arm throws the transverse yoke to the right or to the left, causing the forward steering runners to turn pivotally on their respective king bolts.

- 10 The steering bar is provided on its underside with a transverse strap comprising a fulcrum bar 26 which is arranged under the central slat, and two brackets 27 projecting upwardly from opposite ends of the fulcrum bar and secured to the under side of the steering bar by means of two rivets 8. Two fulcrum pins 28 which are arranged transversely in line and on opposite sides of the central slat, pass vertically through the fulcrum bar and the steering bar, as shown in Fig. 4.

A pivot plate 29 is arranged transversely on the forward, upper surface of the central slat, being securely fastened thereto by means of the vertical rivets 30. On the forward edge near the ends of this pivot plate are two fulcrum sockets or notches 31 which are arranged a distance apart equal to the center to center distance of the fulcrum pins 28. Each of the latter is adapted to engage one of the fulcrum sockets or recesses.

To the central portion of the steering bar is secured a hook 40 which receives the forward end of a longitudinal centering spring 32. This spring is secured at its rear end to the hook-shaped front end of a longitudinal thumb screw 33 which passes horizontally through the central portion of the forward cleat and is provided with a wing nut 34 engaging with the rear face of said forward cleat, thereby permitting the spring to exert rearward pressure on the central portion of the steering bar.

In the normal central position of the front runners, both fulcrum pins of the steering bar engage with both their companion fulcrum sockets, as shown by full lines in Figs. 3, 4 and 6, the parts being yieldingly held in this position by the tension of the centering spring. Upon turning the steering bar horizontally in either direction, together with the front runners connected therewith, this bar swings about an axis formed by one of the fulcrum pins turning in its respective socket while the other fulcrum pin moves forwardly out of its socket, as shown by dotted lines in Fig. 3, thereby further straining the spring and upon releasing the steering bar this spring automatically returns the same back to its normal central position. It is therefore apparent that in this organization of steering mechanism it is possible to retain the front runners yieldingly in their central position by the use of but one spring and still pivot each of the

front runners individually immediately above the rear part of its sliding surface, whereby the runners upon meeting with resistance are less liable to be deflected and therefore renders steering of the sled easier and safer. 70

I claim as my invention:

1. A sled comprising a body, steering runners pivotally connected with said body, a yoke connecting said runners, and a steering bar having a changeable fulcrum and provided with a longitudinal arm which is connected with said yoke. 75

2. A sled comprising a body, steering runners movable horizontally thereon, a transverse yoke pivotally connected with the front parts of said runners, a steering bar having two fulcrum pins and provided with a longitudinal arm which has a pin and slot connection with the yoke, and a pivoting 80 plate or member secured to said body and adapted to be engaged at one part or another by said fulcrum pins. 85

3. A sled comprising a body, steering runners movable horizontally thereon, a transverse yoke pivotally connected with the front parts of said runners, a steering bar having two fulcrum pins and provided with a longitudinal arm which has a pin and slot connection with the yoke, an elastic element 90 attached to the central portion of said steering bar tending to move the same rearwardly relatively to the body. 95

4. A sled comprising a body, steering runners pivoted at their rear ends to said body, 100 a transverse yoke pivotally connecting the front ends of said runners, a steering bar provided with a longitudinal arm which has a pin and slot connection with said transverse yoke, a fulcrum bar attached to said 105 steering bar and provided with a plurality of pins, and a pivot plate arranged on the body and having notches or recesses adapted to receive corresponding pins of the fulcrum bar. 110

5. A sled comprising a body, steering runners pivoted at their rear ends to said body, a transverse yoke pivotally connecting the front ends of said runners, a steering bar provided with a longitudinal arm which has 115 a pin and slot connection with said transverse yoke, a fulcrum bar attached to said steering bar and provided with a plurality of pins, a pivot plate having notches or recesses mating with corresponding pins of 120 the fulcrum bar, and an elastic element attached to the central portion of said steering bar tending to move the same rearwardly. 125

6. A sled comprising a body, two steering runners pivotally mounted for horizontal turning at their rear ends on said body, a yoke pivotally connected at its opposite ends with the front ends of said runners, a steering bar arranged transversely above the body and provided centrally with a for- 130

wardly projecting arm which is pivotally connected with the central part of said yoke, a fulcrum plate arranged transversely on the body and provided at its opposite ends with forwardly-opening fulcrum sockets or notches, a fulcrum bar arranged transversely under the body and connected at its opposite ends with said steering bar, vertical fulcrum pins engaging with said sockets or notches and each connected at its upper and 10 lower ends with said steering bar and fulcrum bar, and a centering spring connected at its front end with the central part of said fulcrum bar and at its rear part with said body.

CHARLES D. ORCUTT.
